UNITED STATES PATENT OFFICE.

RALPH S. PRYCE AND FRANK E. FRENCH, OF LINCOLN, AND WILBUR S. BOSTDER, OF CHADRON, NEBRASKA.

SELF-FEEDING PENCIL.

Application filed January 25, 1926. Serial No. 83,625.

To all whom it may concern:

Be it known that we, RALPH S. PRYCE, FRANK E. FRENCH, and WILBUR S. BOSTDER, citizens of the United States, residing at Lincoln, Lincoln, and Chadron, respectively, in the counties of Lancaster, Lancaster, and Dawes, respectively, and State of Nebraska, have invented new and useful Improvements in a Self-Feeding Pencil, of which the following is a specification.

The object of this invention is to provide a pencil designed to carry a plurality of leads in a magazine, and to bring these leads, one at a time, into a central channel where they are acted upon by a plunger serving to advance the lead to be used to operative position with reference to the point of the pencil.

A further object is to provide a device of this type in which all of the elements maintain a fixed relation with reference to each other, except the plunger and the means for advancing said plunger.

A further object is to provide for feeding a new lead from the magazine to a central slotted stem, by the mere rotation of the pencil as a whole, without the necessity of rotating a pick-up device independently of the barrel, as in all previous constructions of this general type.

A further object is to mount the main structural elements within the barrel in such manner that there will be a firm and substantial support therefor, without the possibility of accidental displacement.

A further object is to provide particular means for retaining the lead being used, in operative position, a three-point gripping and holding device being employed, involving the use of a resilient member specially mounted and bearing on the lead, a split element providing resilient fingers, and a tapered pencil point thru which the lead passes and which engages the lead at or adjacent to the projecting portion thereof, constituting the point per se.

A further object is to provide for the cooperation of the upper end of the plunger with the spiral member, so that the opera-

tive end of the plunger shall maintain a 50 particular position with reference to the channel formed in the tubular stem.

A further object is to provide, in one form of the device, for the cutting of a spiral channel, for cooperation with the plunger, directly 55 in the inner wall of a tube within the barrel of the pencil.

With the foregoing and other objects in view, the invention consists in the novel construction and arrangement of elements described, illustrated and claimed, it being understood that modifications may be made within the scope of the claims, without departing from the spirit of the invention.

In the drawings forming part of this application,

Figure 1 is a view of the pencil in longitudinal section.

Figure 2 is a transverse section on line 2—2 of Figure 1.

Figure 3 is a section on line 3—3 of Figure 1.

Figure 4 is a section on line 4—4 of Figure 1.

Figure 5 is a view in elevation showing 75 the central tubular stem, having longitudinal slots therein, and adapted to receive the leads, one at a time, from the magazine formed between the stem and the barrel of the pencil.

Figure 6 is a perspective view of the plunger.

Figure 7 is a view in elevation, showing 85 the spiral element by means of which the plunger is advanced longitudinally of the barrel.

Figure 8 is a view in elevation of a point block, the upper end of which is to be rigid with reference to the upper end of the tapered point of the pencil, but is detachable with reference to the lower end of the barrel of the pencil.

Figure 9 is a section on line 9—9 of Figure 1.

Figure 10 is a view showing the manner 95 of mounting the spring clip on the outer side of the barrel.

Figure 11 is a detail view showing a slot

in the tubular spiral cover, permitting this element to be soldered to the spiral of Figure 7.

Figure 12 is a section on line 12—12 of Figure 5, showing the manner of mounting a spring which bears on the lead fed from the magazine, by the plunger.

Figure 13 is a perspective view showing the central element of Figure 4, by means of which the leads are guided into the channel of the stem.

Figure 14 is a fragmentary view in vertical section, showing a modification in which a spiral channel is cut directly in the wall of the bore of a tube within the barrel or casing.

The barrel of the pencil is designated 10, the tapered point is shown at 11, and a cap 12 is mounted as disclosed below, and covers an eraser 13, the cap having an upper flared end 14, and the lower end of the cap, as the device is shown in Figure 1, abutting the upper end of the barrel.

A spring clip 15 is mounted on the barrel or casing, and may include an enlarged end portion 16, and ears such as 17 which project from the upper end, at the sides thereof, and which pass thru a slot or slots in the barrel, and which are then deflected on the inner side, and pressed down so that they will lie flush with the surface of the inner wall of the barrel. The curvature or form of the freely movable portions of the clip may be varied as desired.

The stem of tubular form, and shown in detail in Figure 5, constitutes an important feature of the device and is provided with an elongated slot 20, extending thru the upper portion 21 of the stem, this slot terminating with an end wall at 22 where a continuous annular connecting member is provided, it being understood that the structure is integrally formed.

The lower portion 23 of the stem of Figure 5, is slotted longitudinally as shown at 24, and a longitudinal flange or lip 25 extends alongside of the slotted portion, outwardly to the wall of the barrel, a magazine being provided between the main portion of the stem, or the channeled portion thereof and said inner wall of the barrel. The lower portion of the stem of Figure 5 is provided with an external thread 27, and with a tapered end 28, and within the longitudinal bore of the threaded portion, we mount a special spring of the form shown in Figure 12, this spring being adapted to bear against the lead advanced by the plunger, and serving a special purpose in aiding in the holding of the lead in proper position, so that there will be no shifting of the latter in use. The spring is designated 30 and it is provided with a lower deflected end 31, with a deflected portion 32, and with a U-shaped portion 33 adapted to

fit over the wall of the stem at the point shown in Figure 12, and also illustrated in Figure 5. The wall is made thinner at this point, so that the end of the spring properly engages the wall and lies between the latter and an annular channel formed in the point block, described below.

This point block is illustrated in elevation in Figure 8, and includes a tubular portion 35, a flanged portion or head 36, and a flanged portion 37. The block or tubular element of Figure 8 further includes a slotted and tapered portion provided with spring fingers 38, adapted to engage the lead at a point between the point of engagement thereof by the spring 30 and the reduced end 11' of the pencil point 11. This three-point contact with the lead is considered to be of very great importance from a practical standpoint. The point block of Figure 8 constructed as specified, is threaded onto the lower end of the stem of Figure 5, and is soldered to the tapered point 11 of the pencil, but is detachable with reference to the lower end of the barrel of Figure 1. The length of the magazine 40 is such that a full length lead, advanced to writing position, by the plunger, will be engaged at all three points of contact, as indicated roughly by the dotted line 41 in Figure 1. The lead in use, as represented in that view, is designated 42.

The clip 15, or any other suitable device or design, may be regarded as an indicating member, and in order to cause the entrance of one of the leads into the channel portion of the stem of Figure 5, the plunger is retracted to the limit of its upward movement, by the means indicated below, and the barrel, including all of the elements therein or mounted thereon, is rotated thru one revolution, so that the indicating device, considered for convenience, as the clip 15, is brought back to the same position, or to the upper side, when the pencil is held horizontally, or approximately so, and the flange or lip 25 will then be in the position of Figure 4, and will have picked up a lead, so that it will fall by gravity thru slot 24, into the channel portion 24' of the stem.

A center block 44 includes flanges 45 which engage the inner wall of barrel 10, and the block 44 is secured to the portion 22 of Figure 5 by crimping or providing slightly flattened sides as shown in Figure 9, whereby a firm contact is provided or secured. This element 44 is connected by soldering to barrel 10, as shown at 44', the object being to avoid any accidental displacement of the elements within the barrel, at this point, or at any other part of the construction.

The plunger 47 is tapered as shown in Figure 1 and is designed to lie in close contact with the adjacent wall of the channel in the

stem of Figure 5, and the end of the plunger contacts directly with the lead after the latter has been received within the channel, as illustrated in Figure 4. The upper limit of 5 movement of the plunger is slightly above the lower edge or end of element 44, and the limit of movement of the plunger in the opposite direction is slightly below the upper end or edge of portion 36 of the point block 10 of Figure 8, also shown in Figure 1, so that an absolutely clear space is provided for the lead being received.

The plunger is shown in detail in Figure 6, as well as in Figure 1, and it is provided 15 with a flattened portion 48, and with an upper flattened portion 49. The upper end portion is turned over, or downwardly, at 20 50, and is then turned outwardly or laterally at 51, all of this upper end portion being flattened and the proportions being such that a particular type of cooperation with the spiral of Figure 7 is assured. The element of Figure 7 may comprise a tubular member provided with a spiral channel 25 extending entirely thru the wall thereof, the channel being open at both ends. The tube is designated 53, and the channel is shown at 30 54, this channel being engaged by the portion 51 of the plunger, whereby upon the rotation of the spiral, in the manner described below, the plunger will be advanced for imparting longitudinal thrust to the lead. The manner of cooperation between 35 the upper portion of the plunger of Figure 6 and the element or elements engaged thereby, insures the holding of the lower end of the plunger in engagement with the wall of the channel at the side shown in Figure 1. This is also an important feature in operation.

A spiral cover 55 is illustrated in Figure 11, and is shown in Figure 1 as surrounding the spiral member of Figure 7, and this cover 55 is firmly secured to the outer wall 45 of the spiral 53 by means of solder applied thru slots 56 in the cover 55. The upper end of this element 55 is of greater diameter than the remaining portion thereof, and is roughened or provided with shallow corrugations 50 in the manner shown in Figure 2, whereby the cap 12 of Figure 1 is caused to provide substantial engagement with the spiral cover, and especially with the upper end 55' thereof which constitutes the corrugated 55 portion. In advancing the plunger 47, the user of the article rotates the cap 12, and thereby imparts rotary movement to the spiral of Figure 7 which in turn, imparts longitudinal movement to the plunger. The cap 12 covers the eraser 13, as previously indicated, and the latter is held in any suitable manner, as indicated at 13', where the upper end of the spiral cover is shown as being crimped against the side wall of the eraser. It will, or course, be understood that

the plunger is movable in both directions by imparting rotary movement to the cap as indicated, but that no other relative rotary movement of parts is required, since the lead is brought to the position of Figure 4 by the 70 rotation of the entire pencil, as already fully disclosed. In order to maintain the inner structure in permanent fixed position with reference to the barrel (exclusive of the means for advancing the plunger), contact 75 with the barrel is provided at the upper end of the spiral cover, also at the point of engagement with center block 44, and thirdly by means of the point block of Figure 8, having the relative position to the other 80 parts illustrated in Figure 1.

In the modified form of Figure 14, a spiral channel 54' is formed directly in the tubular member 55', the upper end of this element last named being provided with 85 shallow longitudinal corrugations for the purpose previously indicated. The laterally extending portion at the upper end of the plunger of Figure 6, will cooperate directly with the spiral channel 54', so that the use 90 of a spiral such as that shown in Figure 7, and an independent element as a cover therefor may be avoided, although both forms of construction are equally practicable, and after extended experimental work, no defect in mechanical construction and no objectionable feature in operation has developed, but on the other hand, the device has been proven to be highly efficient and almost incapable of imperfect operation during use. 100

It should be stated that a washer 60 is mounted during the assembly of the device, between the center block and the spiral tube of Figure 7, another washer 61 being mounted at the other end of the spiral, and a ring 105 or disk 62 is placed over this washer, and subsequently, forced down under pressure to bring these various elements into close relation, so that they will operate in a sense as one device. The end portion of the stem 110 is then crimped at 63.

The pencil is recharged with leads directly from the box in which they are supplied by the trade for pencils of this class, and it is only necessary to detach the upper end 115 of the point block 36 from the lower end of the barrel 10 in order to provide for the entrance of the leads to the magazine.

Having thus described the invention, what is claimed as new, is:—

1. In a pencil, a barrel, a pencil point, projecting from one end of the barrel, a rotatable element projecting from the other end, a tubular slotted stem including a flange 125 extending outwardly from the edge of the slotted portion and tangentially with reference to the exterior wall of the tubular stem, a plunger for advancing a lead into the stem, said stem being spaced inwardly from the walls of the barrel to provide a 130

- magazine, and the plunger including a laterally projecting element, a tubular member having a spiral formed therein engaged by the projecting element of the plunger, the stem extending the full length of the tubular element and barrel and being rotatable by the barrel, devices for mounting the tubular stem in fixed relation to the barrel, said spiral being rotatable by the rotatable element for advancing the plunger and imparting movement to a lead within the channel, and a point block rigid with the pencil point and stem and detachably connected with the barrel.
2. In a pencil, a barrel, a pencil point, projecting from one end of the barrel, a cap projecting from the other end, a tubular slotted stem including a flange extending outwardly from the edge of the slotted portion and tangentially of the inner and outer walls of the tubular stem, a plunger for advancing a lead into the stem, said stem being spaced inwardly from the walls of the barrel to provide a magazine, and the plunger including a laterally projecting element, a tubular member having a spiral formed therein engaged by the projecting element of the plunger, the stem extending the full length of the tubular element and barrel and being rotatable by the barrel, and devices comprising a center block engaging the barrel and a point block engaging the pencil point and barrel, for mounting the tubular stem in fixed relation to the barrel, the point block being rigidly connected with the stem and pencil point and detachably connected with the barrel, said spiral being rotatable by the cap for advancing the plunger and imparting movement to a lead within the channel.
3. In a pencil, a barrel, a pencil point and a cap abutting opposite ends of the barrel, a tubular slotted stem fixed within the barrel and including an outwardly extending flange forming a lead guiding device, the flange being positioned tangentially with reference to the inner and outer walls of the tubular stem, a magazine being provided between the stem and the barrel from which leads are moved consecutively into engagement with the flange and thence thru the slot of the stem, a plunger slidable within the stem, a tube having a spiral therein for engaging the plunger and providing close contact thereon at the free end of the plunger with the inner wall of the stem, and a spiral cover surrounding this tube and fixed thereto, said cap detachably engaging the spiral cover, the cover engaging the inner wall of the barrel and guiding the end of the plunger engaged by the spiral.
4. In a pencil, a barrel, means therein providing a magazine, tubular flanged means fixed within the barrel and rotatable thereby, said magazine providing a chamber substantially coextensive with the circumference of the barrel receiving leads moved by gravity one at a time, from the magazine upon the rotation of the barrel and stem simultaneously, means for advancing the leads from the magazine and devices for engaging a lead when advanced from the magazine, at points adjacent to the ends of said lead, and at a point intermediate of the ends.
5. In a pencil, a barrel, means therein providing a magazine, tubular flanged means fixed within the barrel and rotatable thereby, said magazine providing a chamber substantially coextensive with the circumference of the barrel, said tubular flanged means receiving leads moved by gravity one at a time, from the magazine upon the rotation of the barrel and stem simultaneously, means for advancing the leads from the magazine and devices for engaging a lead when advanced from the magazine, at points adjacent to the ends of said lead, and at a point intermediate of the ends, said means last named including a resilient member.
6. In a pencil, a barrel, means for receiving leads therein means for feeding the leads, a point for the pencil, and a point block mounted within said pencil point, the point block including an end enlargement rigidly connected with the pencil point and detachably connected with the barrel, a tubular stem projecting into the point block and a spring adapted to project thru the stem and engage a lead within the bore thereof, said spring including a U-shaped portion extending laterally thru the wall of the stem and engaging the outer face thereof.
7. In a pencil, a barrel, a pencil point extending from one end of the barrel, a tubular point block fixed in the pencil point and detachably connected with the barrel, the end of the point block constituting one end of a magazine, a tubular stem provided with a longitudinal slot and a laterally extending flange, the stem extending longitudinally thru the barrel for its full length and the flange maintaining fixed relation with reference to the barrel, the stem rigidly engaging the point block, a spring within one end portion of the stem for maintaining the leads upon the initial movement thereof from the magazine, in alignment with the axis of the stem, independently of other holding devices, a center block constituting the other end of the magazine and fixed in the barrel and rigid with the stem, a plunger movable thru the stem and devices for advancing the plunger.
8. In a pencil, a barrel, a pencil point extending from one end of the barrel, a tubular point block fixed in the pencil point and detachably connected with the barrel, the end of the pencil block constituting one end of a magazine, a tubular stem provided with a longitudinal slot and a laterally extending

- flange, the stem extending longitudinally thru the barrel for its full length and the flange maintaining fixed relation with reference to the barrel, the stem rigidly engaging the point block, a spring within one end portion of the stem for maintaining the leads upon the initial movement thereof from the magazine, in alignment with the axis of the stem, independently of other holding devices, a center block constituting the other end of the magazine and fixed in the barrel and rigid with the stem, a plunger movable thru the stem and devices for advancing the plunger, these devices comprising rotatable means having a spiral channel and a cap for the barrel having detachable connection with the rotatable means and movable therewith, when attached thereto.
9. In a pencil, a barrel, a pencil point extending from one end of the barrel, means
- 5 within the barrel defining a magazine, the opposite walls of the magazine being spaced to an extent exceeding the diameter of the leads to be inserted, to permit of free movement thereof, a tubular and slotted stem 25 rigidly mounted centrally of the barrel, a plunger, a spiral and a tubular spiral cover rigidly connected therewith for advancing the plunger into the stem, and a cap having detachable connection with the means advancing the plunger, said means last named carrying engaging devices for effecting non-rotatable connection between these means and the cap when attached.
